[57] ABSTRACT

A method and apparatus for selectively fusing a toner image configuration to a support material while not effecting fusing of randomly deposited toner in non-image areas. The fuser utilizes a heat source which creates a sufficient amount of heat in the dense toner image areas on the support material to cause toner to permanently adhere thereto. The unbonded toner in the non-image areas may then be readily removed after fusing to produce a high quality reproduction. The fusing method and apparatus of the invention utilizes a series of diagonally oriented parallel wires to support the support material during fusing to minimize uneven heat conduction from the support material.

METHOD AND APPARATUS FOR SELECTIVE FUSING

BACKGROUND OF THE INVENTION

This invention relates in general to fusing a visible image to a support material and, in particular, to an improved selective fusing method and apparatus.

More specifically, this invention relates to a selective fusing method and apparatus wherein a heat source selectively fuses developer material lying in image configuration onto a support material while randomly deposited toner lying in non-image areas is not bonded thereto. The method and apparatus according to the present invention includes an improved platen for supporting the support material during fusing wherein a series of diagonally oriented parallel wires minimize the heat conduction loss between the support material and the support member maintaining it. The unbonded background toner particles are thereafter removed by any convenient method to form a high quality reproduction of an original document or the like.

In the process of xerography, a xerographic surface comprising a layer of photoconductive material on a conductive backing is given a uniform electric charge on its surface and then is exposed to the subject matter to be reproduced by various projection techniques. This exposure discharges a plate in accordance with the light intensity reaching it thereby creating a latent electrostatic image on or in the plate. Development of the image is effected by developers which may comprise, in general, a mixture of suitable, pigmented or dyed, resin base powder, hereinafter referred to as toner, which is brought into contact with the surface by various well-known development techniques. During such development of the image, the toner powder is brought into surface contact with the photoconductive coating and is held there electrostatically in a pattern corresponding to the latent electrostatic image. Thereafter, the developed xerographic image may be transferred to a support material to which it may be fixed by any suitable means such as heat fusing.

Several techniques have been employed in the prior art to accomplish the aforementioned fusing of the transferred developed image to the support material. One well-known method of fusing the toner powder to the support material has been by the application of heat to melt the particles into a bond with the support material. Such a manner of fusing is disclosed in the U.S. Pat. No. 2,297,691 to Carlson wherein a heating element is placed near the surface of the support material bearing a developed image whereupon the heat from the heat source will melt the particles into a bond with the paper. However, the employment of such heat to fuse the toner image to the support material has presented the problem of also fusing toner particles deposited in non-image areas to the support material, which will mar the quality of the reproduction. Generally, upon exposure of a photoconductor surface, a residual electrostatic charge remains in the non-image areas of the surface which during development will randomly attract toner particles thereto. Such attracted toner particles in the background areas will transfer with the developed image onto the support material and, when fused into a final reproduction, will produce undesired bonded toner in non-image areas. The problem of fusing toner in background areas becomes especially critical when the reproduction is to be utilized as a master copy for making subsequent copies, since when background toner is fused to a master, the subsequent copies made therefrom tend to readily reveal background development even when the background fused toner is not observable on the master.

A technique of fusing has been utilized in the prior art to overcome the deficiencies of fusing toner particles to non-image areas as occurs in the basic heat fusing systems. Such an improved fusing system is disclosed in the U.S. Pat. No. 3,411,932 to Malone et al. wherein a selective heat fusing technique is employed that effects fusing of only toner lying in image areas of the support material. Thereafter, the non-bonded background particles may be readily removed to

produce a high quality reproduction of the original subject matter. However, such a system of selective fusing has encountered several problems in creating a high quality reproduction. Selective fusing is based upon the technical principal that toner is densely adhering in developed image areas whereupon a particular heat wavelength radiation level is selected to cause the dense image material to melt into a bonding relationship with the support material without effecting bonding of the toner adhering in non-image areas. Generally, the background toner materials do not densely affix to the non-image areas of the surface and, therefore, the cooling rate of these particles is sufficient to prevent their melting into a bonding relationship with the support material at certain heat levels that do cause bonding of image particles.

The selective bonding of image toner to the exclusion of background particles is effected because the support material absorbs significantly less impinging radiation at certain wavelengths than toner adhering in image and background areas thereof. Accordingly, the energy input per unit area of the support material is less than the adhering toner particles and thus a level of energy may be selected which allows adequate cooling of background toner to prevent their bonding while at the same time melting the denser particles in image areas into a bond with the support material. However, selective fusing requires an accurate application of energy to the support surface to achieve the desired result of not fusing background toner. This accurate application further requires that the temperature remain uniform on the support material and not be raised in certain areas to an energy level which prevents the aforementioned desired cooling of background toner.

However, the support material has heretofore been supported on a flat platen which during selective fusing creates a variation of heat conduction from the material to the platen to thereby cause the energy level in certain areas of the support material to be greater than in others wherein the high heat levels can be sufficient to effect the aforementioned undesired bonding of the background toner. The variation of heat conduction generally is created because of the differences in platen temperature over its surface and the non-uniformity of contact between the platen and the support material. Further, since the temperature of the support material is a critical consideration in selective fusing, it becomes important to control its temperature prior to fusing. However, the use of a flat support platen also retains heat after fusing which preheats subsequently used support material to an extent to interfere adversely with the selective fusing process.

One solution to the problems presented by a flat platen during selective fusing would be an attempt to obtain uniform conduction of heat from the support material during fusing which is, however, virtually impossible. Therefore, it becomes desirable to attempt to thermally isolate the support material from the platen member as much as possible to minimize any contact therebetween and prevent the non-uniform heat conduction difficulty. By so minimizing heat conduction, the temperature of the support medium may be more effectively controlled to effect the desired level of energy transfer between the particles and the support material for accurate selective fusing. Also, a minimum contact platen alleviates the problem of preheating the support material because of the retention of energy in the platen from previous fusing operations.

SUMMARY OF THE INVENTION

It is, therefore, an object of this invention to improve the method and apparatus for fusing a toner image to a support material.

Another object of this invention is to improve the method and apparatus for selectively fusing toner adhering to the image areas of the support material thereto.

A further object of this invention is to minimize the contact of the platen maintaining the support material during fusing.

Still another object of this invention is to prevent the pre-heating of the support material before fusing.

These and other objects are obtained in accordance with the present invention wherein there is provided a selective fusing method and apparatus that utilizes a minimum contact platen for supporting a support material during the fusing operation. The improved support platen of the present invention includes a grid member which is supported above a concave reflecting platen to prevent variations in heat conduction from the image bearing support material thereto. As the support material moves across the grid platen, a minimum of heat conduction is produced between the support material and the platen during fusing because of the small physical contact existing therebetween. Such minimum contact not only insures the accurate selective fusing of toner to image areas to the exclusion of non-image particles, but further will not preheat the support material to an extent great enough to cause background residual toner to bond to the support material during fusing. By producing such accurate environmental control of the paper during fusing, the unbonded toner in background areas may be readily removed from the support material after fusing of image toner to produce a high quality reproduction which can be used for such purposes as a master for subsequent copies. Therefore, the present invention presents a novel method and apparatus which improves the selective fusing of toner to image areas to the exclusion of toner randomly adhering to non-image areas.

DESCRIPTION OF THE DRAWINGS

Further objects of the invention together with additional features contributing thereto and advantages accruing therefrom will be apparent from the following description of one embodiment of the invention when read in conjunction with the accompanying drawings wherein:

FIG. 1 is a schematic illustration of a xerographic machine utilizing the selective fusing system of the present invention.

FIG. 2 is a perspective illustration of the selective fusing system of the present invention.

FIG. 3 is a top schematic illustration of the minimum contact platen utilized in the fusing system of the present invention.

DESCRIPTION OF THE PREFERRED EMBODIMENT

Referring to FIG. 1, there is shown for purposes of illustration a schematic view of a drum type automatic xerographic reproducing machine utilizing the present invention. The central element of the apparatus is a drum 1 mounted for rotation and driveable in a conventional direction by motor M. The drum 1 comprises an outer surface having a layer of photoconductive insulating material such as, vitreous selenium, or other suitable surface. A uniform electrostatic charge is placed on the photoconductive surface of the drum by means of a conventional corona charging device 2. The uniformly charged surface on the drum is then moved to an exposure means 3 which may be any well-known device which will expose the charged surface to copy to be reproduced to thereby form a latent electrostatic image of the copy on a photoconductor drum surface in a manner well known in the art.

Following the formation of a latent electrostatic image of the copy to be reproduced, the image on the drum will move to a development device 4 to bring the electrostatic image into contact with developer material, comprising charged toner, to develop the latent image. After development the visible image moves to a transfer means 9 and is transferred from the drum to a sheet of paper or other suitable support material which is brought into contact with the drum by a conventional support material feeding system 5. A second corona charging device 6 applies a charge to a side of the sheet of support material opposite the developed image to facilitate transfer of the toner powder in image form. The toner image on the sheet thereupon moves past the selective fusing system 10 according to the present invention (to be described in detail later) which permanently affixes the toner to the sheet material to form a duplicate of the original copy. A cleaning device 7 contacts the photoreceptor surface after it moves past the transfer

device to remove any residual image material on the surface prior to a subsequent reproduction cycle. It should be clear that other modes of charging, exposing, developing and transfer may be utilized in connection with the present invention.

Referring now to FIG. 2, there is illustrated an embodiment of the selective fusing device 10 of the present invention. The fusing device is positioned to receive the support material after a developed image has been transferred thereto. The fusing device comprises a housing 11 which includes a shaft 12 rotatably mounted across the entire width of the housing at the entrance 13 thereof. The exit end 14 of the housing includes a similar shaft 15 rotatably mounted by suitable means. Each of the shafts 12 and 15 include a roller element adapted to retain therebetween a series of transport belts and each of the belts extend around the two rotatable shafts. The transport belts are any suitable material to carry and transport a sheet or the like of support material from the transfer device and are driven by suitable motor means (not shown) connected to the shaft 15 to move the belts and transport the sheet support material at a desired speed. The belts are further maintained by two roller elements 17 rotatably mounted beneath the non-contact platen 18 and two roller elements 17a rotatably mounted on each side of the focusing area 19 to facilitate the belt passing under the fusing area in a non-interferring manner. Edge guides 20 are mounted at the entrance of the fusing area to contact the two edges of the support material as it moves thereby to insure that the support material passes in a flat condition through the fusing area.

A rotatable shaft 21 is mounted in brackets at the entrance of the fusing area and includes two edge rollers 22 which contact the edge of the support material and positively guide the support material into the fusing area 19. The front of the sheet of support material entering the fusing area is moved therethrough by the rest of the sheet member still in contact with the conveying belts 16. As the sheet is conveyed through the fusing area, the leading edge of the sheet reaches the conveying belts 16 at the exit area 14 of the housing which then pulls the trailing part of the sheet through the fusing area. A pressure roller 23 is rotatably mounted at the exit side of the fusing area to receive the support material from the fusing area for pressing the sheet material into positive contact with the conveying belts and for preventing curling of the sheet. Two additional edge guides 24 are mounted on each side of the housing in the fusing area to maintain the sheet of support material flat during fusing.

The fusing area 19 includes a source of heat energy produced by a conventional means 25 such as, for example, a quartz infrared lamp mounted by suitable means above the path of movement of the image bearing support material. The quartz lamp is connected to a suitable voltage potential (not shown) to create a desired level of heat for suitable fusing and the lamp is surrounded by a cylindrical reflector 26 having a reflective surface to concentrate the heat therefrom to the support material having an image to be fused thereon. The surface of the reflector may be any suitable material which transmits the desired level of heat to the support sheet and may be, for example, a gold surface which creates a high reflectance for an infrared lamp. The toner image to be fused lies on the support sheet in direct confrontation to the quartz lamp whereby the heat therefrom is absorbed by the toner in the image areas. Since the developer in the image areas is relatively densely packed, the cooling rate therein is not sufficient to prevent the toner from melting into a bond with the support material.

However, toner deposited randomly in the non-image areas is generally much less dense than in the image areas and thereby the heat level created by the lamp is insufficient to melt the toner into a bonding relationship with the sheet, since the cooling rate of non-image toner is great enough to prevent melting thereof. Therefore, the image toner is permanently fused to the sheet of support material while the background particles are not bonded which are then in condition to be

readily removed from the support material. After fusing, the sheet is conveyed by suitable means to a removal device 8 where the unbonded background toner is removed from the duplicate. The removal device may be any device capable of removing the background particles such as, for example, disclosed in the aforementioned U.S. Pat. No. 3,411,932 or alternatively, the unbonded toner may be removed by hand. After the unbonded particles are removed, a permanent high quality duplicate of the subject matter to be reproduced is conveyed to a utilization station whereupon it may be removed by an operator or other utilization means.

Referring now to FIG. 2 and FIG. 3, the platen 18 supporting the support material during fusing is illustrated and comprises a grid 27 of thin parallel wires which are diagonally strung between two elongated members 28. Any number of wires may be utilized in connection with the present invention depending on the degree of support and heat isolation desired for the support material. A concave reflecting surface 29 is mounted beneath the diagonally oriented wires to reflect a controlled level of heat to the support material during fusing. The wires support the support material with a minimum of contact during fusing to prevent heat conduction therebetween and thereby thermally isolate the support material from the platen to produce a higher degree of control of the temperature for selective fusing by reducing uneven heat conduction as produced by a flat platen surface. Further, the provision of a minimum contact platen 18 in the present invention does not pre-heat the support material when initially conveyed into the fusing area since the plurality of wires do not retain heat as a flat surface does. The wires are diagonally oriented to prevent the wires from contacting a particular area of the support material as the sheet passes under the fusing lamp. Therefore, it should be apparent that the present invention provides a more controlled temperature environment for effecting selective fusing of a toner image to a sheet of support material as compared to prior art devices.

In the above description there has been disclosed an improved method and apparatus for selectively fusing a toner image to a support material to the exclusion of toner adhering to the background areas thereof. The surface to be developed was described for convenience of illustration as being that of a xerographic drum, but the invention may be used to fuse toner images produced on other well-known photosensitive members in the form of plates, belts, webs or coated papers. Further, it is within the scope of the present invention to bond toner images to other forms of support material than sheets as disclosed herein, such as, for example, webs and the like.

While the invention has been described with reference to a preferred embodiment, it will be understood by those skilled in the art that various changes may be made and equivalents may be substituted for elements thereof without departing from the true spirit and scope of the invention. In addition, many modifications may be made to adapt a particular situation or material to the teachings of the invention without departing from its essential teachings.

What is claimed is:

1. A method for selectively fusing developer material supported in image configuration on a support medium to effect a permanent bond therebetween to the exclusion of fusing ran-

5 domly deposited developer material supported in non-image areas of the support medium comprising the steps of

10 applying a predetermined level of heat to a support medium bearing developer material in image configuration and randomly deposited developer materials in non-image configuration to fuse the developer material in image configuration to the exclusion of developer material lying in non-image areas and

15 thermally isolating the support medium from heat conduction during application of said predetermined level of heat by supporting the support medium with a low heat retaining platen while the toner is being heated, said platen contacting the support medium over a small area to effectively eliminate heat transfer between platen and support medium.

2. A method for selectively fusing developer material supported in image configuration on a support medium to effect a permanent bond therebetween to the exclusion of fusing randomly deposited developer material supported in non-image areas of the support medium comprising the steps of

20 applying a predetermined level of heat to a support medium bearing developer material in image configuration and randomly deposited developer materials in non-image configuration to fuse developer material in image configuration to the exclusion of developer material lying in non-image areas,

25 and supporting the support medium with a grid platen to eliminate heat conduction from the support medium during fusing.

3. Apparatus for fusing toner to a support medium comprising

30 a source of heat energy for heating toner to bond the toner to a support medium and,

35 a low heat retaining platen for supporting the support medium while toner is being heated, said platen contacting a support medium over a small area to effectively eliminate heat transfer between platen and support medium for thermally isolating a support medium from the platen.

4. The apparatus of claim 3 wherein said source of heat energy includes means for generating heat of a level to bond toner in predetermined quantities to the support medium while leaving toner in less quantities unbonded to the support medium.

5. The apparatus of claim 3 wherein said source of heat energy includes means for generating radiant heat energy.

6. The apparatus of claim 5 further including a reflective surface adapted to reflect heat through the platen to the support medium.

7. The apparatus of claim 3 wherein said source of heat energy includes an infrared lamp.

8. The apparatus of claim 3 further including removal means for removing unbonded toner from a support medium.

9. The apparatus of claim 3 wherein the platen comprises a plurality of elongated wire members.

10. The apparatus of claim 9 wherein the plurality of elongated wire members are diagonally oriented.

11. The apparatus of claim 3 including edge contact means to maintain the support medium in a flat condition during fusing.
